UNITED STATES PATENT OFFICE.

AUGUSTINE SHELBYNE, OF SOUTH PASADENA, CALIFORNIA.

AIR-BRUSH NOZZLE.

Application filed June 4, 1925. Serial No. 34,801.

This invention relates to air brushes and more particularly to air brush nozzles and the object of this invention is to provide an air brush nozzle which will produce a uniform spray.

Another object is to provide an air brush nozzle in which the inner liquid nozzle is formed integral with an outer air nozzle.

These objects are attained by the disclosure herein set forth by the following description of the accompanying drawings, in which:

Figure 1 is a vertical section taken through an air brush having the improved nozzle applied thereto.

Fig. 2 is a front elevation of the air brush nozzle.

Fig. 3 is a section through the air brush nozzle and a portion of the air brush taken on line 3-3 of Fig. 1.

Fig. 4 is a rear end elevation of the air brush nozzle with the cap remover.

Fig. 5 is a side elevation analogous to Fig. 4.

Fig. 6 is a front elevation of the air brush nozzle.

Fig. 7 is a section to the air brush nozzle taken on the line 7-7 of Fig. 6.

Fig. 8 is a front elevation of the cap of the air brush nozzle.

Fig. 9 is a side elevation of the cap.

Fig. 10 is a section through the cap taken on the line 10-10 of Fig. 8.

Referring by numerals to the accompanying drawings, an air brush is generally designated at 10, having a barrel 11 and a delivery head generally designated at 12. The barrel 11 terminates in extension 13 having a tapered bore 14 through which extends a tapered shank 15 formed on the lower portion of the delivery head 12. The shank 15 is provided with a bore 16 which enters a horizontal bore 17 formed in a horizontal portion 18, terminating in a threaded portion 19. The lower portion of the shank 15 is threaded as indicated at 20 and is adapted to receive a coupling 21, carrying a paint tube 22. The head 13 of the barrel 11 has a flat bottom face 23 and an annular depending boss 24.

A cap generally designated at 25 has an opening 26 adapted to receive the boss 24. The cap 25 has a flat face 27 and is held in

place on the extension 13 by a screw 28. The delivery head having the shank 15 is held in place by an expansion coil spring 29 engaging the nut 30. A horizontal bore 31 extends through the barrel 11 and enters an annular recess 32 formed in the extension 13. The shank 15 has an annular recess 33 adjacent the recess 32 and oppositely disposed lateral openings 34 form a passage between the recesses 32 and 33.

The vertical bores 35 extend upwardly from the recess 33 and meet with horizontal bores 36 which enter an annular depression 37 formed in the end of the horizontal portion 18 of the delivery head 12.

The end of the portion 18 has a flat face 38 and is of cylindrical form. The air brush nozzle constituting the invention is generally designated at N and is constructed as follows:

The air brush nozzle is preferably formed from a piece of hexagon brass rod and has a tapered external face 39 which is of slightly less diameter than the hexagon head 40. The inner liquid delivery nozzle is formed within the center of the nozzle and has an internal bore 41 and extends outwardly and rearwardly beyond the head 40 and terminates in a threaded shank 42.

The head 40 has an annular depression 43 and a counter-bore 44 adapted to engage the face 38 and extend over the edge of the cylindrical portion of the portion 18. A plurality of apertures 45 extend inwardly from the depression 43 and enter an annular opening 46 formed in the forward end of the nozzle which forms the end of the outer nozzle 47. The annular opening 46 is threaded as indicated at 46^a and terminates in an internal tapered seat 48 which is of slightly larger diameter than the external diameter of the threads 47.

Four equally spaced lateral apertures 49 are formed in the nozzle and intersect the apertures 45 for a purpose later described. The exterior of the inner nozzle is tapered as indicated at 50 and terminates in a cylindrical tip 51, the interior of the nozzle being tapered as indicated at 52 and terminating in an internal straight bore 53, within the tip 51.

In order to concentrate the flow of air passing through the apertures 45 and annu-

lar openings 46, a cap generally designated at C is provided. The cap C is in the form of a cylindrical body having an internal tapered bore 54 terminating in a flat face 54^a, and has a flat outer face 55 and an opening 56 is formed in the center of the cap.

The exterior of the cap has a flat annular face 57 and upset threads 58 are formed thereon. A tapered face 59 of slightly larger diameter than the exterior of the threads 58, is formed on the cap on the end opposite the annular face 57, within an internal recess 60, in a head 60^a. The threads 58 of the cap C are adapted to engage the threads 47 of the nozzle and when screwed into place the tapered face 59 engages the seat 48 and the opening 56 surrounds the tip 51, thus providing a uniform clearance generally designated at A between the interior of the opening 56 and the exterior of the tip 51.

It will be noted that the annular face 57 of the cap C, fits within the annular opening 46 of the nozzle, and that a clearance is left between the end 47 of the nozzle and the internal recess 60 of the cap.

From the above it will be seen that an air brush nozzle having a uniform air passage surrounding the liquid nozzle is provided. If desired, a spreader attachment may be provided, generally designated at 61, which is adapted to fit over the exterior of the nozzle. The spreader attachment is in the form of a frustum conical body 62, having an internal tapered bore 63 adapted to engage the tapered face 39 of the nozzle. The spreader is provided with a pair of oppositely disposed extensions or wings 64, through which extend passages 65 entering an internal annular recess 66, having a passage 67 adapted to register within the lateral aperture 49. The spreader attachment is held in place on the nozzle by a leaf spring 68 which engages the inner side of the cap C and projects into the recesses 69 formed in the wings 64. The nozzle may be used with or without the spreader attachment.

A needle valve 70 having a reduced diameter point 71 extends through the bore 17 and inner nozzle 50, the reduced point 71 extending through the tip 51. The needle valve is adapted to regulate the flow of the liquid from the inner nozzle and is mounted in a cylinder generally designated at 72, which is screw threaded into the portion 18 of the delivery head, and is normally held in the position shown in Fig. 1, by an expansion spring 73 within the cylinder 72 and engaging a head 74 on the stem 70^a of the needle valve 70.

A sleeve 75 surrounds the cylinder 72 and a nut 76 is screw threaded on the end of the needle valve. A trigger 77 is pivotally mounted at 78 on an arm 79 and a link 80

forms a connection between the trigger and the sleeve 75.

A check valve 81 is mounted in a recess 82 and engages a seat 83. The check valve has a stem 84 which engages a pin 85 on the trigger 77 and is held seated by an expansion spring 86 mounted within a fitting 87 adapted to receive a hose coupling 88 secured to a hose 89.

A passage 90 is formed in an extension 91, formed integral with the barrel 81 and communicates with the bore 31 therein. An air regulating device generally designated at 92 mounted on the end of the barrel 11.

The air brush operates in the usual manner, namely, when the trigger 77 is pulled back, air will pass through the passage 90, the bore 31, into the recess 32, through the openings 34 into the recess 33, thence through the vertical and horizontal bores 35 and 36 where it is delivered to the air brush nozzle. The air entering the nozzle will pass through the plurality of apertures 45, thence between the internal bore 54 of the cap C and the exterior of the inner nozzle 50, the flow of the air being concentrated as it passes through the clearance A. It will be understood that when the trigger is pulled back to admit air, the needle valve is also pulled back by the mechanism shown, in order to increase the flow of paint.

When the spreader attachment is in the position shown in Figs. 1, 2 and 3, a portion of the air passing through the apertures 45 will enter the lateral openings 47 and pass into the annular recess 66, in the spreader attachment, thence through the passage 67, and passages 65, which will direct the oppositely disposed streams of air against the atomized mixture issuing from the nozzle proper, and produce a fan-shaped spray.

When it is desired to use the nozzle without the spreader attachment which produced the fan-shaped spray, the spreader attachment is rotated 45° in either direction, which will bring the passage 67 out of registration with any one of the apertures 49, thus cutting off the air entering the passages 65. When the spreader attachment is in the position shown in Figs. 1, 2 and 3, a vertical fan-shaped spray is produced and when the spreader attachment is rotated 90° a horizontal fan-shaped spray is produced.

It will be particularly noted that the inner liquid nozzle and outer air nozzle are formed integral and that when the cap C is screwed into place the opening 56 in the cap will be positively and accurately centered around the tip 51 of the inner liquid nozzle, due to the tapered faces of the cap engaging the tapered seat in the end of the outer air nozzle.

From the above it will be seen that an air brush nozzle is provided which will produce a uniform spray.

Various changes may be made without departing from the spirit of the invention as claimed.

What is claimed is:

- 5 1. An air brush comprising an outer air nozzle having an internally tapered seat at the outer end thereof and an internally threaded portion, a cap having external threads to engage with the internally threaded portion of the outer nozzle, an external tapered face adapted to engage the internal tapered face of the outer air nozzle, an inner liquid nozzle formed integral with said outer air nozzle, said inner liquid nozzle 10 having an internal bore and a tapered portion with a tip extending through an opening formed in the center of the cap.
  - 15 2. An air brush nozzle comprising an outer air nozzle having an internal tapered seat and an internally threaded portion, a cap, said cap having an external thread and an external tapered face adapted to engage the internal tapered face of said outer air nozzle and an inner liquid nozzle formed integral 20 with said outer air nozzle, said inner liquid nozzle having an internal bore, a tapered portion and a tip extending through an opening formed in the center of said cap.
  - 25 3. An air brush nozzle comprising an outer air nozzle, an inner liquid nozzle formed integral with said outer air nozzle, said inner liquid nozzle having a threaded extension adapted to be screwed into the end
- of a delivery head of an air brush, said outer nozzle having an internal tapered seat, a cap 35 having a tapered face adapted to engage said internal seat of said outer air nozzle, said inner liquid nozzle having a tapered portion terminating in a tip adapted to extend through an opening in said cap, there being 40 an annular row of apertures lying parallel with said inner nozzle forming air passages through said air brush nozzle.
4. An air brush nozzle comprising an outer air nozzle, an inner liquid nozzle formed integral with said outer air nozzle, said inner liquid nozzle having a threaded extension adapted to be screwed into the end of the delivery head of an air brush, said outer nozzle having an internally threaded section and a tapered internal seat on the outer edge thereof, a cap having external threads to engage with the internal threads of the outer nozzle, the cap having an annular internal recess, the inner wall of said recess being 45 tapered to fit the internal tapered seat of the outer nozzle, the said inner liquid nozzle having a tapered portion terminating in a tip adapted to extend through an opening in said cap, there being an annular row of 50 apertures lying parallel with said inner nozzle forming passages through said air brush.

In testimony whereof I have signed my name to this specification.

A. SHELBURNE.
